UNITED STATES PATENT OFFICE

GEORGE BASIL KING, OF EDGBASTON, BIRMINGHAM, ENGLAND

GRAMOPHONE

Application filed October 16, 1929, Serial No. 400,031, and in Great Britain October 25, 1928.

This invention relates to gramophones and refers more particularly to gramophones of the kind having automatic means for discharging spent needles and replacing them by fresh ones, the present invention relating particularly to a new or improved construction of magazine for holding the needles.

A needle magazine constructed in accordance with the present invention comprises a box like casing having a hinged or movable side so that a needle package containing a row of needles arranged in parallel relationship can conveniently be placed in position, the magazine also including means for positioning the needle package, means for guiding the row of needles and spring means for feeding the row of needles and an ejecting plunger for ejecting the end needle of the row from the magazine into a needle holder.

The box like casing may be made in two halves hinged together and a base or magazine carrier may be provided for receiving the magazine proper, the base or carrier having means for retaining the magazine in its proper relationship thereto.

The positioning means to position the needle package within the magazine may include pins which register with openings in the needle package and may also include a spring pressed plate exerting pressure on one side of the needle package.

The means for feeding the row of needles towards one end may take the form of a spring drum and flexible member connected to a pusher, and the pusher may be provided with a finger piece so that it can be withdrawn by hand when an empty needle package is to be removed and a fresh one inserted.

In connection with needle magazines for gramophones, the gramophone is provided with means for operating a plunger on the magazine, and a further feature of the present invention consists in providing a device automatically to sever the mechanical connection between the plunger operator and the plunger when it is desired to remove the magazine for recharging or for any other purpose.

The means for severing the mechanical connection between the plunger operator and

the plunger may be actuated from a locking lever or member which is employed to retain the magazine in its base or carrier.

Referring to the drawings:

Figure 1 is a view in side elevation. 55

Figure 2 is a plan view.

Figure 3 is an end view.

Figure 4 is a section on line 4-4 of Figure 2.

Figure 5 is a section on line 5-5 of Figure 6. 60

Figure 6 is a section on line 6-6 of Figure 5.

Figure 7 is a section on line 7-7 of Figure 6. 65

Figure 8 is a section on line 8-8 of Figure 6, showing the magazine only.

Figure 9 is a section on line 9-9 of Figure 5, showing the magazine only.

Figure 10 is a perspective view showing a needle package suitable for use in the magazine illustrated. 70

In the construction illustrated, the magazine comprises a body 1 and a hinged side 2 attached to the body by the hinge 3. 75

The parts 1 and 2 are both of somewhat box like form, the back of the part 1 being closed by a plate 4 retained in position by screws 5.

The body 1 is provided in its face with a recess 6 for receiving a needle package 7, while the part 2 is provided with a loose plate 8 behind which springs 9 are disposed pressing the loose plate 8 forwardly against the side of the needle package. 80

The plate 8 is, however, prevented from leaving the part 2 by screws 10 passing loosely through holes 11. 85

The face of the plate 8 is slotted longitudinally at two positions as shown at 12. 90

Slidably mounted in the part 1 is a pusher 13 having a pair of spaced fingers 14 which extend through slots 55 in the part 1 and enter the slots 12 in the plate 8.

These fingers 14 engage behind the row of needles 15. 95

The pusher is connected by a flexible member 16 to a rotatable drum 17 within which is mounted a flat coiled spring 18 of the clock spring type. The drum 17 is rotatably 100

mounted upon a pin 19 attached to the part 1. The arrangement is such that the spring 18 places a tension on the flexible member 16 and tends to draw the pusher 13 towards the right hand end as seen in Figure 6. The flexible member 16 is taken over a guide pin or roller 20 as shown in Figure 5.

The pusher 13 is further provided with a finger piece 21 attached to the pusher by a stem 22 passing through a slot in the plate 4, the purpose of the finger piece 21 being to enable the pusher to be withdrawn when the magazine has been emptied to enable a fresh needle package to be inserted.

The needle package may be similar to that described in my specification No. 31,040 of 1928, and may include a sheet metal clip 24 containing the row of needles 15 retained between the lugs 25 and 26, the clip 24 also having holes 27.

When this needle package is to be placed in the magazine the holes 27 are made to engage with pins 28 in the magazine, the needle package being positioned thereby, and the part 1 of the magazine is further provided with a projection 29 which passes between the lugs 26 of the needle package and engages the end needle of the row so as to form a guide for said needle while it is being ejected.

It will be understood that the fingers 14 extend through the slot 30 in the back of the clip 24.

As each needle is ejected from the magazine by means hereinafter described, the row of needles 15 is fed forward by the pusher 13 by a distance equal to the diameter of one needle, and during such feeding movements the row of needles is guided between ribs 31 on the plate 8 and 32 on the part 1, these ribs preventing the needles from over-riding each other.

The two halves 1, 2, of the magazine proper are locked together by means of a small eye bolt 33 pivoted at 34 to a lug 35 on the part 1 and by a nut 36 on the eye bolt engaging lugs 37 on the part 2.

The base member or carrier is shown at 38 and it is recessed at 39 for receiving the base of the magazine. The base member 38 is provided with a portion 40 to which is pivoted a locking or retaining lever 41 engaging over the top of the magazine so as to retain it in position on the base. A spring 42 is provided adapted to act upon either of two plates 43, 44, associated with the boss of the lever 41 to retain the lever either in the position shown in Figure 3 or in a released position.

Near one end the part 1 is provided with a sliding pin 45 under which is a spring 46, the sliding pin having a head 47 to which is attached a plunger 48 for ejecting the end needle of the row.

It will be seen that the head 47 is provided

with an inclined face 49 and the head 47 is adapted to be engaged by a spring 50 connected to an operating plunger 51 which may be mounted on the gramophone and operated by any suitable means.

Normally the plunger 51 reciprocates the spring 50 so as to reciprocate the pin 45 and the plunger 48, but the mechanical connection between the plunger 51 and the head 47 which is formed by the spring 50 can be severed by the crank arm 52 on the lever 41, the arrangement being such that when the lever 41 is moved into its released position, the crank arm 52 is turned so as to pull the spring 50 away from the head 47.

Thus the act of releasing the magazine from its base 38 also automatically releases the spring 50 from the head 47 so that the magazine can be removed from its base 38, the spring 46 causing the pin 45 to rise and carry with it the plunger 48 thus freeing the plunger from the needle package 24 and enabling the latter to be removed if required.

When the magazine has been recharged and is replaced in its base, the spring 50 will automatically re-engage the head 47 by reason of the fact that the hooked end 53 of the spring 50 will ride over the incline 49 and engage on the upper surface of the head 47.

The needle package 24 is provided with a hole 54 opposite the end needle of the row, i. e. the first needle to be ejected, and a similar hole is provided in the lower edge of the needle package.

In order to prevent the end needle of the row from dropping out, I may provide a removable cover fitting over that end of the needle package where the hole 54 is placed.

The needle package may be placed in the magazine with this cover in position and one end of the recess 6 may be enlarged to provide room for the cover which is withdrawn as soon as the needle package is in position in the magazine.

In order to facilitate the loading of a new needle package into the magazine, a spring actuated catch 56 may be provided, the catch being pivoted at 57 (see Figures 1 and 2) and having a finger piece 58 by which it may be released after the fresh needle package has been inserted and the magazine closed.

The catch 56 may be acted upon by a spring 59 tending to retain it in the position shown in Figure 1 and a stop may be provided to prevent it moving beyond this position.

The finger piece 21 may be shaped so that when it is pulled back it will automatically push aside the catch 56.

Instead of releasing the finger piece 21 by hand after the magazine has closed, I may provide means whereby it is automatically released by means associated with the clip 41.

What I claim then is:—

1. A magazine for needles comprising a two part casing, said parts being movably

- associated together, a loose plate in one part, a spring acting between said plate and said casing part, means for positioning a needle package in the casing, an ejecting plunger 5 for delivering the needles from the magazine one by one, a drum rotatably mounted on the casing, a spring acting upon said drum and tending to rotate it, a pusher slidably mounted within the casing and acting upon the needles, a flexible member connected to said drum and to said pusher, said pusher operating to advance the needles to the delivery point, and ribs on one of said casing parts and on said loose plate for guiding the needles as they move to the delivery point.
2. A magazine for needles comprising a two part casing, said parts being movably associated together, a loose plate in one part, a spring acting between said plate and said casing part, means for positioning a needle package in the casing, an ejecting plunger for delivering the needles from the magazine one by one, a drum rotatably mounted on the casing, a spring acting upon said drum and tending to rotate it, a pusher slidably mounted within the casing and acting upon the needles, said pusher having fingers engaging in slots in one casing part and in the loose plate, a flexible member connected to said drum and to said pusher, said pusher operating to advance the needles to the delivery point, and ribs on one of said casing parts and on said loose plate for guiding the needles as they move to the delivery point.
3. A magazine for needles comprising a casing, said casing having a movable slide through which a needle package containing the needles is inserted therein, means for positioning a needle package in the casing, an ejecting plunger for delivering the needles from the magazine one by one, a head to which said plunger is attached, a separate sliding pin associated with said head, said pin being guided in the casing, a spring acting on said pin whereby said pin and said plunger are returned to the raised position after being depressed for delivering a needle, means for moving the needles to the delivery point and a separable mechanical connection between said plunger and said head.
4. A magazine for needles comprising a casing, said casing having a movable side through which a needle package containing the needles is inserted therein, means for positioning a needle package in the casing, an ejecting plunger for delivering the needles from the magazine one by one, a head to which said plunger is attached, a sliding pin associated with said head, said pin being guided in said casing, a spring acting on said pin, whereby said pin and said plunger are returned to a raised position after being depressed for delivering a needle, in combination with an operating plunger and means
5. A magazine for needles comprising a casing, said casing having a movable side through which a needle package containing the needles is inserted therein, means for positioning a needle package in the casing, an ejecting plunger for delivering the needles from the magazine one by one, a head to which said plunger is attached, a sliding pin associated with said head, said pin being guided in said casing, a spring acting on said pin, whereby said pin and said plunger are returned to a raised position after being depressed for delivering a needle, in combination with an operating plunger and a spring forming a separable mechanical connection between said plunger and said head.
6. A magazine for needles comprising a casing, said casing having a movable side through which a needle package containing the needles is inserted therein, an ejecting plunger for delivering the needles from the magazine one by one, a head to which said plunger is attached, a sliding pin associated with said head, said pin being guided in said casing, a spring acting on said pin, whereby said pin and said plunger are returned to a raised position after being depressed for delivering a needle, in combination with an operating plunger, means forming a separable mechanical connection between said plunger and said head, a base member on which the magazine is adapted to fit, locking means for retaining the magazine on the base member, and means associated with said locking means for disengaging the mechanical connection between said plunger and said head when said locking means are released.
7. A needle magazine for needles comprising a box like casing, said casing comprising two parts movably associated together, one half of said casing having a recess therein, a needle clip containing the needles, means for positioning said clip in said recess, a loose plate associated with the other of said parts, said plate being adapted to engage said needle clip for holding it in said recess, an ejecting plunger for delivering the needles from the magazine one by one, means for moving the needles to the delivery point, and means for guiding the needles as they move to the delivery point.
8. A needle magazine for needles comprising a box like casing, said casing comprising two parts movably associated together, one half of said casing having a recess therein, a needle clip containing the needles, means for positioning said clip in said recess, a loose plate associated with the other of said parts, a spring acting between said plate and said casing part, whereby said plate engages said needle clip for holding it in said recess, an ejecting plunger for delivering the needles from the magazine one by one,

means for moving the needles to the delivery point, and means for guiding the needles as they move to the delivery point.

9. A magazine for needles comprising a casing, said casing having a movable side through which a needle package containing the needles is inserted therein, means for positioning the needle package in said casing, an ejecting plunger for delivering the needles from the magazine one by one, a head to which said plunger is attached, a sliding pin associated with said head, said pin being guided in said casing, a spring acting on said pin, whereby said pin and said plunger are returned to the raised position after being depressed for delivering a needle, a projection associated with said head, and separable means engaging said projection for depressing said head and said plunger.

10. A magazine for needles comprising a casing, said casing having a movable side through which a needle package containing the needles is inserted therein, means for positioning the needle package in said casing, an ejecting plunger for delivering the needles from the magazine one by one, a head to which said plunger is attached, a sliding pin associated with said head, said pin being guided in said casing, a spring acting on said pin, whereby said pin and said plunger are returned to the raised position after being depressed for delivering a needle, a projection associated with said head, in combination with an operating plunger, and means forming a separable mechanical connection between said plunger and said projection.

In witness whereof I affix my signature.
